[57] CLAIM

The ornamental design for a combined bottle and support bracket therefor, as substantially shown and described.

DESCRIPTION

FIG. 1 is an exploded perspective view of a combined bottle and support bracket thereof showing my new design;

FIG. 2 is an elevational view, the opposite side being a mirror image thereof;

FIG. 3 is an elevational view looking from the right of FIG. 2;

FIG. 4 is an elevational view looking from the left of FIG. 2;

FIG. 5 is a top plan view; and

FIG. 6 is a bottom plan view thereof.
